UNITED STATES PATENT OFFICE.

JOSEPH SCHMITZ, OF SAN FRANCISCO, CALIFORNIA.

TRACK-SANDER.

No. 906,308.

Specification of Letters Patent.

Patented Dec. 8, 1908.

Application filed March 17, 1908. Serial No. 421,707.

To all whom it may concern:

Be it known that I, JOSEPH SCHMITZ, a subject of the Emperor of Germany, and a resident of San Francisco, in the county of San Francisco and State of California, have invented a new and Improved Track-Sander, of which the following is a full, clear, and exact description.

This invention relates to track sanders and more particularly to devices of this kind used in connection with railway rolling stock, especially locomotives.

An object of the invention is to provide a simple and efficient track sander, which can be applied to railway rolling stock of various kinds, which is inexpensive to manufacture, and by means of which sand can be distributed in a plurality of directions and delivered to the track at a plurality of points.

20 A further object of the invention is to provide a device of the class described which is operable from a point remote from the sander, which has means for distributing the sand in a plurality of directions, which has normally closed outlet valves controlling the flow of sand therefrom, and which when empty can be easily filled with sand.

The invention consists in the construction and combination of parts to be more fully described hereinafter and particularly set forth in the claims.

Reference is to be had to the accompanying drawings forming a part of this specification, in which similar characters of reference indicate corresponding parts in both views, and in which—

Figure 1 is a side elevation showing a portion of a railway locomotive having my track sander applied thereto; and Fig. 2 is 40 an enlarged, longitudinal section of the sander.

Before proceeding to a more detailed explanation of my invention, it should be clearly understood that while the same is particularly useful in connection with railway rolling stock such as locomotives and the like, it can also be applied to other vehicles and similar devices in which it is sometimes necessary to provide sand or other gritty material at the wheels or other traction members to prevent slipping of the latter. I have shown the sander in the accompanying drawings as applied, for example, to a railway locomotive, but wish to emphasize the fact that I do not wish to limit myself to this particular use for my invention. It is

necessary frequently, to apply sand to railroad tracks, to prevent slipping of the driving wheels of the locomotive when the track is wet, covered with snow, or otherwise rendered slippery. To apply the sand most effectively it is necessary to permit it to escape from the sanding reservoir, at both rails, and preferably at a plurality of points, and by means of my sander the sand can be distributed in a plurality of directions, that is, to both rails, and if so desired, at a number of points of each rail.

Referring more particularly to the drawings, 10 represents a locomotive having the usual boiler 11 and the cab 12. Upon the boiler is mounted a sand reservoir or chamber 13 fashioned from any suitable material, such as sheet iron, and preferably of cylindrical form. The reservoir 13 has a suitable base 14 formed to fit snugly upon the boiler and adapted to be secured thereto in any convenient manner, for example, by means of screws or bolts. The reservoir 13 has a rounded, preferably spherical top or dome 15, fashioned, like the reservoir and the base, from sheet iron or other material adapted to the purpose. At the bottom of the reservoir 13, and extending in a direction parallel to the length of the boiler, is an inverted V-shaped partition 16, extending partly to the top of the dome 15. The partition 16 serves to direct the sand to the opposite sides of the reservoir, as will appear more clearly hereinafter.

The reservoir 13, at the opposite sides, that is, at each side of the boiler, has a downwardly and laterally disposed outlet tube 17 communicating with a conduit 18 leading to a point adjacent to the driving wheels and the track rails, to direct the sand most efficiently to the latter. The openings of the outlets 17 at the bottom of the reservoir 13 are interiorly threaded and have correspondingly threaded upwardly tapered nozzles 19 mounted therein. Above the nozzles 19, and spaced therefrom are substantially vertical cylindrical members 20, which extend through suitable openings in the dome 15. Within the cylindrical members 20 are arranged movable tubes 21 which have guides 22 controlling the movement of the tubes 21 within the cylindrical members 20. Each of the tubes 21 fits over the tapered end of one of the nozzles 19 and when in a depressed position prevents the escape of sand through the nozzles 19.

The dome 15 has arms 23 provided with bearings 24 in which is journaled a spindle 25. The spindle has rigid arms 26 each of which carries a threaded stem 27 secured in a correspondingly and interiorly threaded upper end of each of the tubes 21. The spindle 25 has a further rigid arm 28, at the end of which is a counterweight 29. At one end, the spindle 25 has another rigid arm 30 connected by means of a link 31 with a lever 32 located preferably, in the cab of the locomotive.

The counterweight 29 tends to hold the spindle 25 in a position such that the arms 26 are depressed and the tubes 21 are held in position at the nozzles 19, which prevents the escape of sand through the outlet 17. By suitably operating the lever 32, the spindle 25 can be partly rotated through the link 31, thereby lifting the tubes 21 from the nozzles and permitting the escape of the sand. By merely releasing the lever 32 the counterweight will automatically close the escape openings of the sand reservoir. It will be understood that the partition 16 directs the sand in opposite directions to the nozzles 19. If so desired, I may provide a plurality of such escape openings and have corresponding conduits for directing the sand to a plurality of points adjacent to each rail.

The dome 15 has a suitable opening provided with a removable cover 33 to permit the reservoir to be filled with sand. The cover 33 may be of any preferred form, and may, for example, have a handle 35 at the inside and a rim 36 engaging between suitable extensions 37 of the dome to hold the cover in position. Upon each of the tubes 21, at the end projecting from the cylindrical member 20 is mounted a laterally extended bell or cap 38 projecting over the open end of the cylindrical member 20 and serving to prevent the entrance of rain, other moisture, or the like, into the reservoir, through the cylindrical members.

Having thus described my invention, I claim as new, and desire to secure by Letters Patent:

1. A device of the class described, comprising a sand reservoir having an outlet, a hollow member arranged within said reservoir above said outlet and having an opening outside of said reservoir, and a member movable within said hollow member and operable simultaneously to close said outlet and said opening.

2. A device of the class described, comprising a sand reservoir having an outlet, a hollow member arranged adjacent to said outlet and spaced therefrom, said hollow member extending to the outside of said reservoir and having an opening at the outside, a tubular member within said hollow member, means for guiding said tubular member within said hollow member, and means for

operating said tubular member to close said outlet, said tubular member having means for closing said opening of said hollow member when said outlet is closed.

3. A device of the class described, comprising a sand reservoir having outlets at the opposite sides, hollow members arranged above said outlets and spaced therefrom, said members projecting from said reservoir and being open at both ends, tubular members arranged movably within said hollow members, means for guiding said tubular members within said hollow members, said tubular members serving to close said outlets in predetermined positions and projecting through said hollow member to the outside of said reservoir, said tubular members carrying caps at the outside of said reservoir, and means for simultaneously operating said tubular members, said caps serving to close said hollow members when said outlets are closed.

4. A device of the class described, comprising a reservoir having at opposite sides outlets, inwardly directed tapered nozzles at said outlets, a doubly inclined partition between said nozzles and serving to direct the sand uniformly to said nozzles, cylindrical guide members arranged above said nozzles and projecting from said reservoir, tubular members slidable within said cylindrical members and arranged to fit over said nozzles to close the same, means for simultaneously operating said tubular members from a point remote from said reservoir, and means for normally holding said tubular members in engagement with said nozzles to close the same.

5. A device of the class described, comprising a reservoir having at opposite sides outlets, inwardly directed tapered nozzles at said outlets, a doubly inclined partition between said nozzles and serving to direct the sand uniformly to said nozzles, guide members arranged above said nozzles and projecting from said reservoir, tubular members slidable within said guide members and arranged to fit over said nozzles to close the same, means for simultaneously operating said tubular members from a point remote from said reservoir, means for normally holding said tubular members in engagement with said nozzles to close the same, means for guiding said tubular members within said guide members, and means carried by said tubular members for closing said guide members when said outlets are closed.

In testimony whereof I have signed my name to this specification in the presence of two subscribing witnesses.

JOSEPH SCHMITZ.
